UNITED STATES PATENT OFFICE.

OSCAR W. SCHMIDT, OF MANKATO, MINNESOTA.

DOUBLE-WEAR HARNESS ATTACHMENT.

Application filed August 23, 1928. Serial No. 301,473.

This invention relates to an attachment for harness and has for its object to provide a simple and inexpensive reinforcing element for that portion of the harness which is most 5 easily worn out, namely, the joints of the leather parts with the hardware.

Another object of the invention resides in the provision of such a device which is constructed as a unit and which may be readily 10 applied to the harness without the use of harness-makers' tools or skilled labor.

Other objects and advantages of the invention will be apparent from the following description when taken in connection with the 15 accompanying drawing; in which

Figure 1 is a fragmentary perspective view of a breeching strap with the invention applied thereto.

Figure 2 is a sectional view taken on line 20 2—2 of Figure 1; and

Figure 3 is a perspective view of the attachment per se, the same being shown in its operative position in dotted lines.

Referring to the drawing in more detail 25 the numeral 1 designates generally a piece of harness, here shown as a breeching strap, although it is to be understood that the reinforcement to be described is intended for use in connection with any and all joints between the straps and the hardware of the 30 harness.

The several straps 2, 3 and 4 of the harness are attached to the metal ring 5 in the usual way and the attachment to be described is inserted 35 between the ring and the loop portions of the straps so as to prevent wear on the loops until such time as the attachment is worn through, thereby greatly extending the life of the harness.

40 The attachment consists merely of a strip of leather 6 and a metal loop 7. The loop 7 is provided with a flat lip or foot 8 by means of which it is riveted or otherwise connected to the strip as indicated by the numeral 9. From an inspection of the drawing it will be 45 noted that the loop 7 projects from the foot 8 at an angle slightly greater than a right angle and is therefore inclined at an acute angle to strip 6, as indicated in Figure 3.

50 The strip 6 is of a width equal to the external width of the loop 7 throughout the greater portion of its length but is notched at both sides of its other end as indicated by numeral 10 so as to provide the relatively narrow 55 portion 11 which is adapted to be inserted through loop 7 when the attachment is put

in place on the harness. In this connection it should be noted that the shoulders 10 serve as a stop to limit the movement of the narrow end of the strip through the buckle 7. 60

Portion 11 of the strip 6 is also tapered toward its free end so as to provide a relatively thin end 12 which will more readily conform to the structure of the harness and permit the usual sliding band 13 to be 65 brought back into position to lock the parts in place.

In applying the attachment to the usual harness construction it is only necessary to disengage the usual buckles found on harness straps such as breeching straps and slide the loop 7 over the strap until the strip 6 is brought into position where it forms a lining for the loop which engages ring 5. The portion 11 of the strip 6 is doubled over upon the 70 main body of the strip and its end passed through loop 7 until the shoulders 10 on the strip engage the edges of the loop. The band 13 is now slid into place and caused to tightly 75 clamp the tapered portion 12 of the strip 6 against the body of the harness strap and also serves as a stop to prevent movement of the loop 7 along the strap. 80

I am aware that other devices have been 85 provided for increasing the life of harness by reinforcing the strap loops but such prior devices are either made of metal or else are too expensive and cumbersome to be of practical value or else require special tools and an experienced harness maker to install them. 90 The present invention, on the other hand, is simple and inexpensive in construction involving only a narrow strip of leather or the like to which a one-piece metal loop is secured at one end thereof. The invention, further- 95 more, may not only be attached to the harness at the factory but also may be readily applied by the teamster, farm hand, or other person having to do with draft animals, without the use of tools and in a minimum of 100 time.

In accordance with the patent statutes I have described what I now believe to be the best embodiment of my invention, but I do not wish to be understood thereby as limiting 105 myself or the scope of the invention, as many changes and modifications may be made without departing from the spirit of the invention; all such I aim to include in the scope of the appended claims. 110

What I claim as new and desire to secure by Letters Patent is:

1. A reinforcement for a strap loop, including a strip of leather having one end of a width slightly greater than that of the loop to be reinforced, the opposite end of said strip being slightly reduced in width, a metal loop secured to the wider end of said strip and adapted to receive the narrower end of said strip when the latter is placed in operative position.
- 10 2. A reinforcement for a strap loop, including a strip of leather having one end of a width slightly greater than that of the loop to be reinforced, a metal loop fixed to said end of the strip, the opposite end of the strip being of a width substantially that of the interior of the loop and providing shoulders

adapted to engage the side walls of the metal loop when the relatively narrow end of the strip is passed into the loop.

- 5 3. In a harness including a ring, a strap having a loop interlocked with said ring and a band encircling said strap, the combination of a strip of leather lining the interior of said loop, a metal loop fixed to one end of said strip and passed over a portion of said strap, the opposite end of said strip being beveled and providing a wedging action in conjunction with said band to lock the strip in place when the band is slid along the strap to operative position.

OSCAR W. SCHMIDT.
